UNITED STATES PATENT OFFICE.

WALTER LLOYD, OF ANTIGO, WISCONSIN.

ROAD MACHINE FOR SNOW.

Application filed September 12, 1924. Serial No. 737,512.

To all whom it may concern:

Be it known that I, WALTER LLOYD, a citizen of the United States, and resident of Antigo, in the county of Langlade and State 5 of Wisconsin, have invented certain new and useful Improvements in Road Machines for Snow; and I do hereby declare that the following is a full, clear, and exact description thereof.

10 This invention relates to road machines and is particularly directed for a machine adapted to operate upon a snow covered road.

Objects of this invention are to provide a 15 road machine for handling snow which will operate upon the roadway in a great variety of ways so as to render it suitable for travel, which is adapted to pack any light snow that may be upon the roadway or which will 20 scrape the snow from the roadway, which will roughen up and remove hard frozen cakes from the roadway, and which is easily operated, and may be drawn over the roadway at a relatively high rate of speed.

25 An embodiment of the invention is shown in the accompanying drawings, in which:—

Figure 1 is a side elevation of the device.

Figure 2 is a plan view thereof.

30 Figure 3 is a sectional view on the line 3—3 of Figure 2.

Figure 4 is a sectional view on the line 4—4 of Figure 3.

Figure 5 is a detail of the adjusting means and support for the rear scraper.

35 The machine comprises two side frame members 1 and 2,—the right hand side frame member 2 being materially longer than the left frame member 1. These side frame members are provided with runners 3 (see 40 Figure 4) which, if desired, may be provided with downwardly extending ribs 4 to aid in preventing slipping of the machine while in no way interfering with the free sliding motion thereof. These side frames are 45 joined by a series of bracing members 5, 6, and 7 as may be seen from Figure 2 to secure the desired rigidity, such bracing members being provided with suitable triangular reinforced ends, as illustrated in Figure 50 2. A tongue 9 is secured between suitable clips and by braces to the front member 8 and, if desired, this front member may be pivotally carried in apertured lugs or bosses 10 formed in the forward ends of the members 1 and 2, as shown in Figure 1, so as to permit rocking motion of the tongue 9. It

is to be understood, of course, that where the tongue is employed for attachment to a team of horses that it is of material length, and obviously where the tongue is adapted for 60 attachment to a tractor, it may be materially shorter. It is merely a means of transmitting traction effort to the machine.

The side frame members 1 and 2 are provided with spaced guides 11 and 12, respectively (see Figure 1) within which crossheads 13 and 14 are adapted to travel. These crossheads are secured to a slanting knife 15 which is set diagonally of the machine, as illustrated in Figure 2. The crossheads are apertured and threaded and receive the threaded adjusting rods 16 which extend vertically and are carried in suitable bearings. The upper ends of these rods are provided with bevel gears 17 which mesh 70 with corresponding bevel gears carried by a transverse shaft 18, such shaft being provided with a manipulating hand wheel 19 at its outer end preferably on the right side, as shown. By this means, therefore, the 75 height of the blade may be accurately and easily controlled by the operator.

The rear portion of the side frame members 1 and 2 are provided with relatively heavy bearing portions 20 (see Figure 2) 85 within which trunnions 21 are journaled. These trunnions are rigidly secured to the rear scraper 22. This scraper is set diagonally, slanting towards the right and towards the rear portion of the machine, as 90 may be seen from Figure 2.

Further, it will be noted from Figure 3 that the scraper is provided with marginal flanges for reinforcement and with a beveled bottom edge. The angular adjustment of 95 the scraper is easily secured by providing apertures through the trunnions 21 and corresponding apertures 23 in the stationary hubs or bearing portions 20 (see Figure 5.) Pins 24 are slipped through the appropriate 100 apertures and thus lock the scraper bar at the desired angle.

At a point intermediate the front knife 15 and the rear scraper 22, the side frames 1 and 2 are found provided with guides 25 105 within which crossheads 26 are slidably carried, as may be seen from Figure 4. These crossheads carry the shaft of a rotary member 27 (see Figures 3 and 4) which is provided with a plurality of ribs or vanes 28 110 for a purpose hereinafter to appear. The outer ends of the shaft of the roller 27 is

provided with a sprocket wheel 29 which is connected by means of a chain with sprocket wheel 30 carried by the driving shaft 31 of an engine 32 or suitable motor. If desired, 5 an idler sprocket wheel 33 (see Figures 1 and 2) may be provided on a spring urged rock shaft 34 to secure the requisite tension in the chain drive irrespective of the adjustment of the crossheads 26. As will be seen 10 from Figure 4, the crossheads receive the threaded rods 35 by which their vertical height may be adjusted. The upper ends of these rods 35 are provided with bevel gears 36 which mesh with corresponding 15 bevel gears carried by a transverse adjusting shaft 37. This transverse shaft 37 is provided with an adjusting hand wheel 38 by which the exact height of the roller 27 may be most readily secured. Immediately 20 rearwardly of the roller 27 a pair of vertical screws or rods 39 are positioned. These rods, as may be seen from Figures 1 and 2, are provided with bevel gears 40 at their upper ends which mesh with corresponding 25 bevel gears carried by a transverse adjusting shaft 41. This adjusting shaft is provided with a hand wheel 42 by which the screws may be readily rotated. The screws each carry a cross head 43 which is connected 30 by means of a link 44 with the rear end of a curved shield plate 45. This shield plate, as may be seen from Figure 3, extends from a point materially in advance of the roller 27 to a point rearwardly thereof and 35 is downwardly curved adjacent its rear end. It is hingedly mounted upon a transverse shaft 46 adjacent its forward end and by means of the screws 39 its setting may be easily controlled.

40 The operation of the apparatus is as follows:—If it is desired to operate upon hard packed glassy roadways, the mechanism is set as illustrated in Figure 3. Under these 45 conditions, the knife 5 scrapes up the ice and such ice flows upwardly and rearwardly over the knife. It immediately encounters the rapidly rotating breaker roll 27 which breaks it up into smaller particles easily disposed of. These pass below the shield plate 50 45 and are engaged by the rear scraper 22 and pushed from the roadway due to the slanting setting of such scraper bar. The fact that the ice slabs are broken into small 55 portions by the roller insures their easy handling by the rear scraper bar and prevents the riding of a slab of ice over the rear scraper bar. Even if ice is left upon the roadway by the machine it nevertheless 60 will be sufficiently roughened up and scrapped to afford a secure grip or hold for the wheels of vehicles.

Another use of this machine may be had when snow has just fallen and is relatively light. Under these conditions, the forward 65 knife 15 may be elevated, and the shield

plate 45 may be set either in its elevated or in its lowered position. If it is desired to pack the snow, the shield plate is lowered and the snow is packed downwardly against the roadway,—the rear scraper 22 smoothing off any uneven portions. However, if it is desired to scrape the snow from the roadway, the shield plate 45 is elevated and the rear scraper engages the snow and sweeps it sidewise from the road. The machine is capable of other uses in handling the snow or ice on a roadway, but it is thought that the methods of use enumerated above will give a fair idea of the versatility and effectiveness of the machine.

It will thus be seen that a machine has been provided for operating upon snow roadways which may be easily controlled, which may be adjusted to treat or operate upon the roadway in a variety of ways, and which may be rapidly drawn along the roadway and will prepare it in a manner suitable for subsequent traffic.

Although the invention has been described in considerable detail, it is to be understood that the invention may be variously embodied and is, therefore, to be limited only as claimed.

I claim:

1. A machine adapted to be drawn over a snow covered road comprising a pair of side frames having runner, braces joining said side frames, a diagonally arranged knife extending between said side frames adjacent the front of the machine, a roller provided with vanes and mounted rearwardly of said knife, means for adjusting the height of said roller, a motor for driving said roller, a shield plate extending over said roller and curving downwardly rearwardly of said roller, and an angularly adjustable scraper mounted rearwardly of said shield plate.

2. A machine adapted to be drawn over a snow covered road comprising a pair of side frames having runners, braces joining said side frames, a diagonally arranged knife extending between said side frames adjacent the front of the machine, a roller provided with vanes and mounted rearwardly of said knife, means for adjusting the height of said roller, a motor for driving said roller, a shield plate extending over said roller and curving downwardly rearwardly of said roller, means for raising and lowering the rear end of said shield plate, and an angularly adjustable scraper mounted rearwardly of said shield plate.

3. A machine adapted to be drawn over a snow covered road comprising a pair of side frames having runners, braces joining said side frames, a knife carried by said side frames adjacent the front of the machine, a roller provided with vanes and mounted rearwardly of said knife, means for driving

said roller, a shield plate pivoted in front of said roller and extending rearwardly over said roller and curving downwardly behind said roller, a plurality of vertical screws for independently adjusting the height of said knife, roller, and rear end of said shield plate, transverse shafts geared to said screws and provided with hand

wheels, a rear diagonally extending scraper, and means for locking said scraper in any one of several angular positions.

In testimony that I claim the foregoing I have hereunto set my hand at Aniwa, in the county of Shawano and State of Wisconsin.

WALTER LLOYD.
